ABSTRACT

An antenna device according to the present disclosure includes a first antenna that is oriented in a first direction and transmits and receives a signal with a first polarization, a second antenna that is oriented in a second direction opposite to the first direction and transmits and receives a signal with the first polarization, a third antenna that is oriented in a third direction and transmits and receives a signal with a second polarization, a fourth antenna that is oriented in a fourth direction opposite to the third direction and transmits and receives a signal with the second polarization. The second antenna is provided with a feeding point placed in phase with a feeding point of the first antenna. The fourth antenna is provided with a feeding point placed in opposite phase to a feeding point of the third antenna.

**COMMUNICATION DEVICE AND
COMMUNICATION METHOD**

INCORPORATION BY REFERENCE

This application is based upon and claims the benefit of priority from Japanese patent application No. 2019-183692, filed on Oct. 4, 2019, the disclosure of which is incorporated herein in its entirety by reference.

TECHNICAL FIELD

The present disclosure relates to a communication device and a communication method.

BACKGROUND ART

Technologies using a plurality of antennas for FD (Full Duplex) communication or MIMO (Multiple Input and Multiple Output) communication are disclosed in Mohammad A. Khojastepour, et. al., "The Case for Antenna Cancellation for Scalable Full-Duplex Wireless Communications", Hotnets '11, Nov. 14-15, 2011, Cambridge, Mass., USA, and Ehsan Aryafar, et. al., "MIDU: Enabling MIMO Full Duplex", MobiCom '12, Aug. 22-26, 2012, Istanbul, Turkey. In these literatures, loop interference signals of antennas are cancelled in a plurality of phases.

In a full duplex radio communication device or a radio relay device, a receiving antenna receives a signal while a transmitting antenna transmits a signal. When the frequencies of transmission and reception are the same or close, loop interference from transmission to reception occurs. Specifically, a radio wave emitted from a transmitting antenna serves as interference on the receiving side, which causes the degradation of reception characteristics. Further, there is sometimes a demand for omni-directionality in order to ensure the flexibility of installation of radio communication equipment.

An object of the present disclosure is to provide a communication device and a communication method with omni-directionality and good reception characteristics.

SUMMARY

A communication device according to the present disclosure includes a first directional antenna oriented in a first direction and configured to transmit and receive a signal with a first polarization, a second directional antenna oriented in a second direction opposite to the first direction and configured to transmit and receive a signal with the first polarization and form a first pair with the first directional antenna, a third directional antenna oriented in a third direction obtained by horizontally rotating the second direction by 90° or 180° and configured to transmit and receive a signal with a second polarization orthogonal to the first polarization, a fourth directional antenna oriented in a fourth direction opposite to the third direction and configured to transmit and receive a signal with the second polarization and form a second pair with the third directional antenna, a first feeding point provided in the first directional antenna, a second feeding point provided in the second directional antenna and placed in phase with the first feeding point, a third feeding point provided in the third directional antenna, a fourth feeding point provided in the fourth directional antenna and placed in opposite phase to the third feeding point, and a receiving circuit configured to adjust at least one

2

of an amplitude and a phase of a received signal received by the first pair or the second pair and demodulate the received signal.

A communication method according to the present disclosure includes a step of performing one of transmission and reception by using a first pair including a first directional antenna provided with a first feeding point and a second directional antenna provided with a second feeding point, a step of performing another one of transmission and reception by using a second pair including a third directional antenna provided with a third feeding point and a fourth directional antenna provided with a fourth feeding point, and a step of adjusting at least one of an amplitude and a phase of a received signal received by the first pair or the second pair and demodulating the received signal, wherein the first directional antenna and the second directional antenna transmit and receive a signal with a first polarization, the third directional antenna and the fourth directional antenna transmit and receive a signal with a second polarization orthogonal to the first polarization, the first directional antenna is oriented in a first direction, the second directional antenna is oriented in a second direction opposite to the first direction, the third directional antenna is oriented in a third direction obtained by horizontally rotating the second direction by 90° or 180°, the fourth directional antenna is oriented in a fourth direction opposite to the third direction, the first feeding point and the second feeding point are placed in phase with each other, and the third feeding point and the fourth feeding point are placed in opposite phase to each other.

BRIEF DESCRIPTION OF DRAWINGS

The above and other aspects, features and advantages of the present disclosure will become more apparent from the following description of certain exemplary embodiments when taken in conjunction with the accompanying drawings, in which:

FIG. 1 is a view schematically showing the structure of an antenna device of a communication device;

FIG. 2 is a Y-Z cross-sectional view schematically showing the structure of a patch antenna, which is a first antenna;

FIG. 3 is a view showing isolation characteristics in one antenna;

FIG. 4 is a view showing isolation characteristics in the case of combining received signals of two antennas;

FIG. 5 is a view showing a simulation result of the azimuth directivity of an antenna device;

FIG. 6 is a block diagram showing a communication device according to an example embodiment;

FIG. 7 is a block diagram showing an example of a demodulation signal processing circuit;

FIG. 8 is a block diagram showing a communication circuit according to a modified example;

FIG. 9 is a schematic diagram showing a variable distribution circuit;

FIG. 10 is a perspective view schematically showing the arrangement of a third antenna 3 and a fourth antenna 4 in a second example embodiment;

FIG. 11 is a perspective view schematically showing the arrangement of the third antenna 3 and the fourth antenna 4 in the second example embodiment; and

FIG. 12 is a view schematically showing the structure of an antenna device according to another example embodiment.

EMBODIMENTS

Example embodiments of the present disclosure will be described hereinafter with reference to the drawings. In the

figures, the identical reference symbols denote identical structural elements and the redundant explanation thereof is omitted.

A communication device according to this example embodiment is to be used for a radio relay device for femtocell communications, for example. The radio relay device has both the function of communicating with a terminal and the function of communicating with a base station. Thus, there is a case where the radio relay device transmits a radio signal to a terminal and simultaneously receives a radio signal from a base station. There is also a case where the radio relay device transmits a radio signal to a base station and simultaneously receives a radio signal from a terminal. In such cases, a transmission signal can come to the receiving side, which causes the degradation of the reception characteristics.

An antenna device of a communication device preferably has omni-directionality. In other words, the antenna device preferably covers an azimuth of 0° to 360°. For example, in the case of an antenna device without omni-directionality, the angle and direction of installation are restricted. On the other hand, if an antenna device has omni-directionality, radio communication is achieved regardless of the angle of installation. Particularly, an antenna device that is installed as a radio relay station at home or the like is required to have omni-directionality. In this example embodiment, an antenna device having omni-directionality and capable of reducing the degradation of reception characteristics due to loop interference is provided.

First Example Embodiment

The structure of an antenna device that is used for a communication device according to a first example embodiment is described hereinafter with reference to FIG. 1. FIG. 1 is a perspective view schematically showing the structure of an antenna device 100. The following description is based on the assumption that the antenna device 100 is used for a radio relay station having the function of communicating with a base station and the function of communicating with a terminal. FIG. 1 shows an XYZ three-dimensional orthogonal coordinate system to clarify the description. For example, the Y direction is a vertical direction, and the XZ plane is a horizontal plane. A direction in the XZ plane is an azimuth.

The antenna device 100 includes a first antenna 1 to an eighth antenna 8. The first antenna 1 to the eighth antenna 8 are patch antennas with directivity. The first antenna 1 to the eighth antenna 8 include a front conductor 112 and a back conductor 113 formed on a dielectric substrate 111. The structure of the patch antenna is described later.

The patch antenna has directivity according to the orientation of a radiating element, which is, the orientation of the front conductor 112. The first antenna 1 to the eighth antenna 8 are planar antennas in a flat shape. The first antenna 1 to the eighth antenna 8 are placed parallel to the XY plane.

The first antenna 1, the second antenna 2, the fifth antenna 5 and the sixth antenna 6 are antennas for communication with a base station. By using the first antenna 1, the second antenna 2, the fifth antenna 5 and the sixth antenna 6, radio communication with a base station is achieved. The third antenna 3, the fourth antenna 4, the seventh antenna 7 and the eighth antenna 8 are antennas for communication with a terminal. By using the third antenna 3, the fourth antenna 4, the seventh antenna 7 and the eighth antenna 8, radio communication with a terminal is achieved.

The first antenna 1, the second antenna 2, the fifth antenna 5 and the sixth antenna 6 transmit and receive radio signals of V polarization (vertical polarization). The third antenna 3, the fourth antenna 4, the seventh antenna 7 and the eighth antenna 8 transmit and receive radio signals of H polarization (horizontal polarization).

The first antenna 1, the third antenna 3, the fifth antenna 5 and the seventh antenna 7 are placed on the same XY plane. Thus, the Z positions of the first antenna 1, the third antenna 3, the fifth antenna 5 and the seventh antenna 7 are the same. The first antenna 1, the third antenna 3, the fifth antenna 5 and the seventh antenna 7 are oriented in the -Z direction. The first antenna 1, the third antenna 3, the fifth antenna 5 and the seventh antenna 7 have directivity in the azimuth direction around the -Z axis direction.

Likewise, the second antenna 2, the fourth antenna 4, the sixth antenna 6 and the eighth antenna 8 are placed on the same XY plane. Thus, the Z positions of the second antenna 2, the fourth antenna 4, the sixth antenna 6 and the eighth antenna 8 are the same. The second antenna 2, the fourth antenna 4, the sixth antenna 6 and the eighth antenna 8 are oriented in the +Z direction. The second antenna 2, the fourth antenna 4, the sixth antenna 6 and the eighth antenna 8 have directivity in the azimuth direction around the +Z axis direction.

For example, it is assumed that the first antenna 1, the third antenna 3, the fifth antenna 5 and the seventh antenna 7 have sensitivity in the azimuth range of 0° to 180°, and the second antenna 2, the fourth antenna 4, the sixth antenna 6 and the eighth antenna 8 have sensitivity in the azimuth range of 180° to 360°.

The first antenna 1 and the second antenna 2 are placed facing in opposite directions. A received signal of the first antenna 1 and a received signal of the second antenna 2 are to be combined. Further, a transmission signal is to branch off and to be emitted from the first antenna 1 and the second antenna 2. The first antenna 1 and the second antenna 2 that are oriented in opposite directions to each other form a pair and achieve omni-directionality. A pair of the first antenna 1 and the second antenna 2 is referred to as a first pair. The first antenna 1 and the second antenna 2 are placed so as to overlap each other in the XY plane. The positions of the first antenna 1 and the second antenna 2 in the XY plane correspond to each other.

The third antenna 3 and the fourth antenna 4 are placed facing in opposite directions. The third antenna 3 and the fourth antenna 4 form a pair. A pair of the third antenna 3 and the fourth antenna 4 is referred to as a second pair. A received signal of the third antenna 3 and a received signal of the fourth antenna 4 are to be combined. Further, a transmission signal is to branch off and to be emitted from the third antenna 3 and the fourth antenna 4. A feeding point 13 of the third antenna 3 and a feeding point 14 of the fourth antenna 4 are placed at positions that are mirror images of each other. The third antenna 3 and the fourth antenna 4 that are oriented in opposite directions to each other form a pair and achieve omni-directionality. The third antenna 3 and the fourth antenna 4 are placed so as to overlap each other in the XY plane. The positions of the third antenna 3 and the fourth antenna 4 in the XY plane correspond to each other. The third antenna 3 is oriented in the direction where the direction of the second antenna 2 is rotated by 180° in the horizontal direction (about the Y axis).

The fifth antenna 5 and the sixth antenna 6 are placed facing in opposite directions. The fifth antenna 5 and the sixth antenna 6 form a pair. A pair of the fifth antenna 5 and the sixth antenna 6 is referred to as a third pair. A received

signal of the fifth antenna **5** and a received signal of the sixth antenna **6** are to be combined. Further, a transmission signal is to branch off and to be emitted from the fifth antenna **5** and the sixth antenna **6**. The fifth antenna **5** and the sixth antenna **6** that are oriented in opposite directions to each other form a pair and achieve omni-directionality. The fifth antenna **5** and the sixth antenna **6** are placed so as to overlap each other in the XY plane. The positions of the fifth antenna **5** and the sixth antenna **6** in the XY plane correspond to each other.

The seventh antenna **7** and the eighth antenna **8** are placed facing in opposite directions. The seventh antenna **7** and the eighth antenna **8** form a pair. A pair of the seventh antenna **7** and the eighth antenna **8** is referred to as a fourth pair. A received signal of the seventh antenna **7** and a received signal of the eighth antenna **8** are to be combined. Further, a transmission signal is to branch off and to be emitted from the seventh antenna **7** and the eighth antenna **8**. A feeding point **17** of the seventh antenna **7** and a feeding point **18** of the eighth antenna **8** are placed at positions that are mirror images of each other. The seventh antenna **7** and the eighth antenna **8** that are oriented in opposite directions to each other form a pair and achieve omni-directionality. The seventh antenna **7** and the eighth antenna **8** are placed so as to overlap each other in the XY plane. The positions of the seventh antenna **7** and the eighth antenna **8** in the XY plane correspond to each other. The seventh antenna **7** is oriented in the direction where the direction of the eighth antenna **8** is rotated by 180° in the horizontal direction (about the Y axis).

The fifth antenna **5** is placed on the +X side of the first antenna **1**. The third antenna **3** is placed on the -Y side of the first antenna **1**. The seventh antenna **7** is placed on the +X side of the third antenna **3** and on the -Y side of the fifth antenna **5**. Thus, the first antenna **1**, the third antenna **3**, the fifth antenna **5** and the seventh antenna **7** are arranged in a 2×2 array on the same XY plane. Likewise, the second antenna **2**, the fourth antenna **4**, the sixth antenna **6** and the eighth antenna **8** are arranged in a 2×2 array on the same XY plane.

The first antenna **1** has a feeding point **11**. The feeding point **11** is to feed power to the first antenna **1**. Likewise, the second antenna **2** to the eighth antenna **8** have feeding points **12** to **18**, respectively. The feeding points **12** to **18** are to feed power to the second antenna **2** to the eighth antenna **8**, respectively. When an adjacent antenna is located nearby, there is a possibility that a transmission signal comes to the receiving side, causing interference. A structure to reduce the interference is described hereinbelow.

The XY positions of feeding points of a pair of two antennas correspond to each other. For example, when viewed in the XY plane, the feeding point **11** of the first antenna **1** and the feeding point **12** of the second antenna **2** correspond to each other. Likewise, when viewed in the XY plane, the feeding point **13** of the third antenna **3** and the feeding point **14** of the fourth antenna **4** correspond to each other. When viewed in the XY plane, the feeding point **15** of the fifth antenna **5** and the feeding point **16** of the sixth antenna **6** correspond to each other. When viewed in the XY plane, the feeding point **17** of the seventh antenna **7** and the feeding point **18** of the eighth antenna **8** correspond to each other.

The structure of the patch antenna is described hereinafter. FIG. 2 is a cross-sectional view showing the structure of the first antenna **1**, which is the patch antenna. To be specific, FIG. 2 shows a cross-sectional view along the YZ plane. Note that the basic structure of the second antenna **2** to the eighth antenna **8** is the same as that of the first antenna **1**, and

therefore detailed description thereof is omitted. The first antenna **1** includes the dielectric substrate **111**, the front conductor **112**, the back conductor **113**, a feeder **114**, and a connector **115**. The connector **115** may be a coaxial cable. In this case, the coaxial cable may be connected to the front conductor **112** by soldering or the like.

The dielectric substrate **111** is a parallel flat plate made of a dielectric material such as insulating resin, for example. The front conductor **112** is formed on the -Z side surface of the dielectric substrate **111**, and the back conductor **113** is formed on the +Z side surface of the dielectric substrate **111**. Thus, the front conductor **112** is formed on the front surface of the dielectric substrate **111**. The back conductor **113** is formed on the back surface of the dielectric substrate **111**. Note that the surface on which the front conductor **112** is formed is referred to as an antenna surface side, and the surface on which the back conductor **113** is formed is referred to as a ground surface side.

The front conductor **112** and the back conductor **113** are made of a conducting material such as copper foil, for example. The front conductor **112** is a radiating element that radiates linear polarization. The front conductor **112** is a rectangular pattern with a size according to the frequency of transmission and received signals, the dielectric constant of the dielectric substrate **111** and so on. The back conductor **113** is formed almost entirely on the dielectric substrate **111** excluding the connector **115**. The back conductor **113** is grounded.

The connector **115** is connected to the backside of the dielectric substrate **111**. The connector **115** connects a cable (not shown) to the dielectric substrate **111**. The cable is a coaxial cable, for example, and its conductor serves as the feeder **114**. The feeder **114** reaches the front conductor **112** via a through-hole **111a** provided on the dielectric substrate **111**. The feeder **114** and the front conductor **112** are electrically connected, thereby feeding power. A connecting position of the feeder **114** to the front conductor **112** serves as the feeding point **11**.

The basic structure of the second antenna **2** to the eighth antenna **8** is the same as that of the first antenna **1**. The third antenna **3**, the fifth antenna **5** and the seventh antenna **7** are oriented in the same direction as the first antenna **1**. Specifically, the first antenna **1**, the third antenna **3**, the fifth antenna **5** and the seventh antenna **7** are oriented in the -Z direction. The second antenna **2**, the fourth antenna **4**, the sixth antenna **6** and the eighth antenna **8** are oriented in the opposite direction to the first antenna **1**. Specifically, the second antenna **2**, the fourth antenna **4**, the sixth antenna **6** and the eighth antenna **8** are oriented in the +Z direction. A pair of two antennas, such as the first antenna **1** and the second antenna **2** in the first pair, for example, are placed opposite to each other with their back conductors **113** facing each other.

Referring back to FIG. 1, the first antenna **1**, the third antenna **3**, the fifth antenna **5** and the seventh antenna **7** have an antenna surface on the -Z side. The second antenna **2**, the fourth antenna **4**, the sixth antenna **6** and the eighth antenna **8** have an antenna surface on the +Z side. Specifically, the antenna surfaces of the first antenna **1**, the third antenna **3**, the fifth antenna **5** and the seventh antenna **7** and the antenna surfaces of the second antenna **2**, the fourth antenna **4**, the sixth antenna **6** and the eighth antenna **8** face opposite directions. The first antenna **1**, the third antenna **3**, the fifth antenna **5** and the seventh antenna **7** can emit electric waves in the azimuth range of 0° to 180°. On the other hand, the second antenna **2**, the fourth antenna **4**, the sixth antenna **6** and the eighth antenna **8** can emit electric waves in the

azimuth range of 180° to 360°. Omni-directionality is achieved by combining the first antenna **1** and the second antenna **2**, the third antenna **3** and the fourth antenna **4**, the fifth antenna **5** and the sixth antenna **6**, and the seventh antenna **7** and the eighth antenna **8** in an appropriate phase relationship.

Note that the first antenna **1** and the fifth antenna **5** can use a common substrate as the dielectric substrate **111**. Specifically, two rectangular patterns are formed on the surface of one dielectric substrate **111**. Then, one rectangular pattern is used as the front conductor **112** of the first antenna **1**, and the other rectangular pattern is used as the front conductor **112** of the fifth antenna **5**. Likewise, the second antenna **2** and the sixth antenna **6** can use a common substrate as the dielectric substrate **111**. The third antenna **3** and the seventh antenna **7** can use a common substrate as the dielectric substrate **111**. The fourth antenna **4** and the eighth antenna **8** can use a common substrate as the dielectric substrate **111**.

Further, four antennas oriented in the same direction may use a common substrate as the dielectric substrate **111**. For example, the first antenna **1**, the third antenna **3**, the fifth antenna **5** and the seventh antenna **7** may use the dielectric substrate **111** in common. Further, the second antenna **2**, the fourth antenna **4**, the sixth antenna **6** and the eighth antenna **8** may use the dielectric substrate **111** in common.

The first antenna **1**, the second antenna **2**, the fifth antenna **5** and the sixth antenna **6** are used for transmitting and receiving V polarization. In the case of V polarization, the feeding point is displaced in the -Y direction from the center of the front conductor **112** when viewed in the XY plane from the antenna surface. The third antenna **3**, the fourth antenna **4**, the seventh antenna **7** and the eighth antenna **8** are used for transmitting and receiving H polarization. In the case of H polarization, the feeding point is displaced in the -X direction from the center of the front conductor **112** when viewed in the XY plane from the antenna surface.

The XY position of the front conductor **112** is the same between the first antenna **1** and the second antenna **2**. Specifically, when viewed in the XY plane, the front conductor **112** of the first antenna **1** and the front conductor **112** of the second antenna **2** have the same size and the same shape as each other, and are placed at the same position. The front conductor **112** of the first antenna **1** and the front conductor **112** of the second antenna **2** are placed so as to overlap each other. Further, the feeding point **11** of the first antenna **1** and the feeding point **12** of the second antenna **2** are at the same XY position.

In the first antenna **1** and the second antenna **2**, the feeding point **11** and the feeding point **12** are respectively displaced in the Y direction from the center of the front conductor **112** as described above in order to transmit and receive V polarization. For example, as shown in FIG. 1, the feeding point **11** and the feeding point **12** are displaced in the -Y direction from the center of the front conductor **112** when viewed in the XY plane from the -Z side. Thus, the feeding point **11** and the feeding point **12** are displaced in the -Y direction from the center of the front conductor **112** also when viewed in the XY plane from the antenna surface.

The XY position of the front conductor **112** is the same between the third antenna **3** and the fourth antenna **4**. Specifically, when viewed in the XY plane, the front conductor **112** of the third antenna **3** and the front conductor **112** of the fourth antenna **4** have the same size and the same shape as each other, and are placed at the same position. Further, the feeding point **13** of the third antenna **3** and the feeding point **14** of the fourth antenna **4** are at the same XY position.

In the third antenna **3** and the fourth antenna **4**, the feeding point **13** and the feeding point **14** are respectively displaced in the X direction from the center of the front conductor **112** in order to transmit and receive H polarization. As shown in FIG. 1, the feeding point **13** and the feeding point **14** are displaced in the -X direction from the center of the front conductor **112** when viewed in the XY plane from the -Z side. Thus, the feeding point **13** and the feeding point **14** are displaced in opposite directions from the center of the front conductor **112** when viewed in the XY plane from the antenna surface. For example, when viewed in the XY plane from the antenna surface side (-Z side) of the third antenna **3**, the feeding point **13** is displaced to the left from the center of the front conductor **112**. When viewed in the XY plane from the antenna surface side (+Z side) of the fourth antenna **4**, the feeding point **14** is displaced to the right from the center of the front conductor **112**. The distance of displacement of the feeding point **13** from the center of the front conductor **112** and the distance of displacement of the feeding point **14** from the center of the front conductor **112** are the same.

Therefore, signals are in phase in a pair of antennas with V polarization, and signals are in opposite phase in a pair of antennas with H polarization. Specifically, the first antenna **1** and the second antenna **2** transmit signals in the same phase. The third antenna **3** and the fourth antenna **4** transmit signals in phases shifted by 180°. The feeding point **12** is placed to be in phase with the feeding point **11**, and the feeding point **14** is placed to be in the opposite phase to the feeding point **13**.

Note that the positional relationship between the feeding point **15** of the fifth antenna **5** and the feeding point **16** of the sixth antenna **6** is the same as the positional relationship between the feeding point **11** and the feeding point **12**. Thus, transmission signals are in phase in the fifth antenna **5** and the sixth antenna **6**. The positional relationship between the feeding point **17** of the seventh antenna **7** and the feeding point **18** of the eighth antenna **8** is the same as the positional relationship between the feeding point **13** and the feeding point **14**. Thus, transmission signals are transmitted in opposite phase in the seventh antenna **7** and the eighth antenna **8**.

The loop interference of a transmission signal is described hereinafter. The state where the second pair of the third antenna **3** and the fourth antenna **4** receives signals while the first pair of the first antenna **1** and the second antenna **2** transmits signals is described first.

The first antenna **1** and the second antenna **2** transmit a common transmission signal to achieve omni-directionality. Specifically, the transmission signal branches off at a distributor and is emitted from the first antenna **1** and the second antenna **2**. Transmission signals transmitted from the first antenna **1** and the second antenna **2** are in phase.

The positional relationship between the third antenna **3** and the first antenna **1** corresponds to the positional relationship between the fourth antenna **4** and the second antenna **2**. Likewise, the positional relationship between the fourth antenna **4** and the first antenna **1** corresponds to the positional relationship between the third antenna **3** and the second antenna **2**. Since the positional relationship of the first antenna **1** to the fourth antenna **4** has symmetry, the amplitude of interference components caused by the loop interference is the same between two antennas in a pair. Specifically, when the first pair performs one of transmission and reception and the second pair performs the other one, the same level of interference occurs in two antennas included in a pair on the receiving side.

Further, as described above, transmission signals transmitted from the first antenna **1** and the second antenna **2** are in phase. The antenna device **100** combines a received signal received by the third antenna **3** and a received signal received by the fourth antenna **4** in opposite phase. This cancels the loop interference of a transmission signal. Specifically, although interference component is generated in both a received signal of the third antenna **3** and a received signal of the fourth antenna **4** due to the loop interference of a transmission signal, two interference components cancel out each other by combining in opposite phases. For example, a received signal of the third antenna **3** contains an interference component caused by a transmission signal of the first antenna **1**, and a received signal of the fourth antenna **4** contains an interference component caused by a transmission signal of the second antenna **2**, and these signals are in phase. By combining the received signal of the third antenna **3** and the received signal of the fourth antenna **4** in opposite phase, the interference components cancel out each other. Likewise, the received signal of the third antenna **3** contains an interference component caused by a transmission signal of the second antenna **2**, and the received signal of the fourth antenna **4** contains an interference component caused by a transmission signal of the first antenna **1**, and these signals are in phase. By combining the received signal of the third antenna **3** and the received signal of the fourth antenna **4** in opposite phase, the interference components cancel out each other. The loop interference of a transmission signal is thereby cancelled. This improves the reception characteristics of the antenna device **100**. This also increases the transmission output because of cancelling the loop interference.

Although the loop interference that occurs when the first pair transmits a transmission signal is described above, the loop interference that occurs when another pair transmits a transmission signal can be cancelled in the same manner. For example, when the third pair transmits a transmission signal also, the positional relationship between the third antenna **3** and the fifth antenna **5** and the positional relationship between the fourth antenna **4** and the sixth antenna **6** are the same. The positional relationship between the third antenna **3** and the sixth antenna **6** and the positional relationship between the fourth antenna **4** and the fifth antenna **5** are the same. Since the four antennas are placed symmetrically, the loop interference of a transmission signal on the receiving side is cancelled.

Next, the state where the first pair receives signals while the second pair transmits signals is described. The positional relationship between the third antenna **3** and the first antenna **1** and the positional relationship between the fourth antenna **4** and the second antenna **2** are the same. The positional relationship between the fourth antenna **4** and the first antenna **1** and the positional relationship between the third antenna **3** and the second antenna **2** are the same.

By the positional relationship between the feeding point **13** and the feeding point **14**, transmission signals are in opposite phase between the third antenna **3** and the fourth antenna **4**. Thus, a received signal received by the first antenna **1** and a received signal received by the second antenna **2** are combined in phase. The loop interference of a transmission signal is thereby cancelled. Specifically, the loop interference component generated in the received signal of the first antenna **1** and the loop interference component generated in the received signal of the second antenna **2** cancel out each other. The loop interference of a transmission signal is thereby cancelled.

Note that a pair on the transmitting side and a pair on the receiving side can be changed as appropriate as long as the directions of polarization on the transmitting side and the receiving side are orthogonal. Specifically, any one of the first to fourth pairs may be used on the transmitting side, another one whose direction of polarization is orthogonal to that of the pair on the transmitting side may be used on the receiving side. In the above-described positional relationships, the loop interference of a transmission signal is cancelled. Further, the antenna device **100** is applicable also to repeater communication using a plurality of antennas on each of the transmitting side and the receiving side, full duplex communication, and so on.

FIG. 3 is a view showing a simulation result of the loop interference on the receiving side. In FIG. 3, when transmitting a transmission signal from the first antenna **1** and the second antenna **2**, isolation characteristics in the third antenna **3** is P1, and isolation characteristics in the fourth antenna **4** is P2, for example. Note that the antenna device **100** is designed at a frequency of 2.6 GHz (example). A design frequency may be set arbitrarily.

FIG. 4 shows a simulation result of isolation characteristics in the case where received signals by the second pair are combined in opposite phase. As shown in FIG. 4, high isolation characteristics are obtained at a design frequency of 2.6 GHz (example). A design frequency may be set arbitrarily. Thus, in this example embodiment, the loop interference of a transmission signal is reduced with a simple structure. This allows an increase in transmission output.

FIG. 5 is a view showing a simulation result of the azimuth directivity of an antenna device. An antenna pattern of the first pair (or the third pair) is shown in the left part of FIG. 5. An antenna pattern of the second pair (or the fourth pair) is shown in the right part of FIG. 5. As shown in FIG. 5, the both pairs have good omni-directionality. Thus, according to this example embodiment, omni-directionality is achieved with a simple structure. Flexibility in installation angle, direction and so on is thereby enhanced.

Although the antenna device **100** includes four pairs of (i.e., eight) antennas in the above description, the number of antennas is not particularly limited. To be specific, the antenna device **100** includes at least two pairs, such as the first antenna **1** to the fourth antenna **4**, for example. The loop interference is thereby suppressed even when transmission and reception are performed simultaneously.

A communication circuit that is used for the antenna device **100** is described hereinafter with reference to FIG. 6. FIG. 6 is a view schematically showing the configuration of a communication device **300** that includes the antenna device **100**. The communication device **300** includes the antenna device **100** and a communication circuit **200**. The communication circuit **200** includes a transmitting circuit **210** and a receiving circuit **220**.

The transmitting circuit **210** includes an in-phase distribution circuit **211** and a modulation circuit **212**. The in-phase distribution circuit **211** is connected to the first antenna **1** and the second antenna **2** through the feeder **114**. The in-phase distribution circuit **211** is connected to the modulation circuit **212**. The modulation circuit **212** modulates an analog transmission signal. The modulation circuit **212** outputs the modulated transmission signal to the in-phase distribution circuit **211**.

The in-phase distribution circuit **211** splits the transmission signal from the modulation circuit **212** and feeds the signals to the first antenna **1** and the second antenna **2** in phase. To be specific, the in-phase distribution circuit **211**

11

splits the transmission signal at a ratio of 1:1 and feeds the signals to the first antenna **1** and the second antenna **2**. An analog distributor may be used as the in-phase distribution circuit **211**.

The receiving circuit **220** demodulates a received signal by digital processing. Further, the receiving circuit **220** adjusts at least one of the amplitude and phase of a received signal from the third antenna **3** and the fourth antenna **4** and demodulates the received signal. The receiving circuit **220** includes an LNA (Low Noise Amplifier) **221**, an LNA **222**, an ADC (Analog to Digital Converter) **223**, an ADC **224**, and a demodulation signal processing circuit **225**.

The receiving circuit **220** is connected to the third antenna **3** and the fourth antenna **4** through the feeder **114**. A received signal by the third antenna **3** is input to the LNA **221** through the feeding point **13** and the feeder **114**. The LNA **221** amplifies the received signal. The received signal amplified by the LNA **221** is input to the ADC **223**. The ADC **223** converts the received signal from analog to digital. The received signal converted into a digital signal is referred to simply as a digital signal. The digital signal from the ADC **223** is input to the demodulation signal processing circuit **225**.

Likewise, a received signal by the fourth antenna **4** is input to the LNA **222** through the feeding point **14** and the feeder **114**. The LNA **222** amplifies the received signal. The received signal amplified by the LNA **222** is input to the ADC **224**. The ADC **224** converts the received signal from analog to digital. The digital signal from the ADC **224** is input to the demodulation signal processing circuit **225**.

The demodulation signal processing circuit **225** demodulates the digital signals from the ADC **223** and **224**. The demodulation signal processing circuit **225** controls a combined complex weight based on the signal quality of a demodulated signal. For example, the demodulation signal processing circuit **225** controls the combined complex weight so as to maximize the SINR (Signal to Interference Noise Ratio).

FIG. 7 is a view showing a circuit example of the demodulation signal processing circuit **225**. The demodulation signal processing circuit **225** includes weight multipliers **231** and **232**, an adder **233**, a demodulation unit **234**, and a control unit **235**. The weight multiplier **231** multiplies the digital received signal from the ADC **223** by the combined complex weight. The weight multiplier **232** multiplies the digital received signal from the ADC **224** by the combined complex weight. In this manner, the weight multipliers **231** and **232** multiply the digital received signal by the combined complex weight and thereby adjust the amplitude and phase of the received signal. The values of the combined complex weight of the weight multipliers **231** and **232** are variable.

The adder **233** adds the digital received signals multiplied by the combined complex weight. The demodulation unit **234** performs demodulation of the digital signal from the adder **233**. The received signal is thereby demodulated. The control unit **235** controls the combined complex weight of the weight multipliers **231** and **232** in accordance with the signal quality of the received signal. In other words, the control unit **235** changes the values of the combined complex weight of the weight multipliers **231** and **232** in accordance with the signal quality of the received signal.

To be specific, the control unit **235** controls the combined complex weight so as to maximize the SINR (Signal to Interference Noise Ratio). The interference components due to the loop interference of a transmission signal are thereby

12

cancelled. The control unit **235** can adjust the values of the combined complex weight so as to minimize the interference.

According to the structure of this example embodiment, a communication device with omni-directionality and good reception characteristics is achieved. For example, the receiving circuit combines two received signals after adjusting the amplitude and phase of the signals. This further improves the reception quality. For example, there is a case where a transmission signal transmitted by the first antenna **1** and the second antenna **2** is reflected on a wall surface, a person or the like and then received by the third antenna **3** or the fourth antenna **4**. Since the interference components containing the reflection of a transmission signal are not in completely opposite phase even with the structure of FIG. 1, there is a possibility that the signal quality of a received signal is degraded.

On the other hand, in this example embodiment, the control unit **235** controls the combined complex weight in accordance with the signal quality of the combined received signal. The interference components containing the reflection of a transmission signal are thereby cancelled. The loop interference of the transmission signal is thereby suppressed, and therefore higher reception quality is obtained.

Further, since the feeding point **14** is placed in opposite phase to the feeding point **13**, the received signals of the third antenna **3** and the fourth antenna **4** can be adjusted easily. For example, the control unit **235** can adjust the value of the combined complex weight by making the initial setting of the combined complex weight to a value for combining in opposite phase (initial value). The control unit **235** sets the initial value of a phase difference between the received signals of the third antenna **3** and the fourth antenna **4** to 180° and sets the initial value of an amplitude difference to 0. The control unit **235** adjusts the combined complex weight based on the demodulated received signal. The control unit **235** optimizes the combined complex weight so as to maximize the signal quality of the received signal. Good reception quality is thereby obtained easily.

Although FIG. 6 shows the receiving circuit **220** for the second pair including the third antenna **3** and the fourth antenna **4**, the similar receiving circuit **220** may be used for another pair of antennas. For example, the receiving circuit **220** may adjust the amplitude and phase of the received signal for the first pair including the first antenna **1** and the second antenna **2** as well. The similar receiving circuit **220** may be used also for the third pair and the fourth pair.

Modified Example 1

The receiving circuit **220** according to a modified example 1 is described hereinafter with reference to FIG. 8. FIG. 8 is a block diagram showing the receiving circuit **220** that performs demodulation by analog processing. The antenna device **100** and the transmitting circuit **210** are the same as those described above, and the description thereof is omitted.

The receiving circuit **220** demodulates a received signal by analog processing. Further, the receiving circuit **220** adjusts at least one of the amplitude and phase of the received signal from the third antenna **3** and the fourth antenna **4** and demodulates the received signal. The receiving circuit **220** includes a variable phase shifter **241**, a variable distribution circuit **242**, and a demodulation circuit **243**.

The variable phase shifter **241** is connected to the feeding point **14** of the fourth antenna **4**. The variable phase shifter

241 adjusts the phase of a received signal by delaying the received signal. The output of the variable phase shifter 241 is connected to the variable distribution circuit 242. Thus, the received signal from the variable phase shifter 241 is input to the variable distribution circuit 242. Further, the variable distribution circuit 242 is connected to the feeding point 13 of the third antenna 3.

The variable distribution circuit 242 combines the received signal by the third antenna 3 and the received signal by the fourth antenna 4. Further, the distribution ratio (combining ratio) of the variable distribution circuit 242 is variable. The variable distribution circuit 242 adjusts the amplitudes of two received signals and combines them.

FIG. 9 is a view showing an example of the variable distribution circuit 242. The variable distribution circuit 242 includes a 3 dB90° hybrid 251, a variable phase shifter 252, and a 3 dB90° hybrid 253. The variable distribution circuit 242 adjusts the phase by using the phase shifter 252 and thereby changes the amplitude of one received signal. The distribution ratio is thereby changed. To be specific, the variable distribution circuit 242 controls the phase based on a control signal from a control circuit 244 and thereby changes the distribution ratio. The 3 dB90° hybrid 253 combines two signals. One output of the 3 dB90° hybrid 253 is input to the demodulation circuit 243. The configuration of the variable distribution circuit 242 is not limited to that shown in FIG. 9.

The received signal combined by the variable distribution circuit 242 is input to the demodulation circuit 243. The demodulation circuit 243 demodulates the combined received signal. The control circuit 244 controls the variable phase shifter 241 and the variable distribution circuit 242 in accordance with the signal quality of the received signal demodulated in the demodulation circuit 243. Specifically, it optimizes the phase and amplitude of the received signal so as to maximize the signal quality of the received signal.

The control circuit 244 outputs control signals for controlling the phase of two received signals to the variable phase shifter 241. The variable phase shifter 241 imparts a phase difference between the two received signals. To be specific, assuming that the variable phase shifter 241 is a variable delay circuit, the control circuit 244 may change a delay time to be given by the variable phase shifter 241. Further, the control circuit 244 outputs a control signal for controlling the amplitude of two received signals to the variable distribution circuit 242. The control circuit 244 changes the distribution ratio in the variable distribution circuit 242. The variable distribution circuit 242 only changes the amplitude ratio between two received signals, and does not change the total received power of two received signals.

The control circuit 244 controls the phase and amplitude of a received signal so as to maximize the SINR (Signal to Interference Noise Ratio). The interference components due to the loop interference of a transmission signal are thereby cancelled. The control circuit 244 can adjust the phase and amplitude of two received signals so as to minimize the interference.

Note that, although the variable phase shifter 241 is placed between the variable distribution circuit 242 and the fourth antenna 4, the variable phase shifter 241 may be placed between the variable distribution circuit 242 and the third antenna 3. Alternatively, the variable phase shifter 241 may be placed both between the variable distribution circuit 242 and the fourth antenna 4 and between the variable distribution circuit 242 and the third antenna 3. The variable

phase shifter 241 is placed so as to adjust the phase of at least one of received signals from the third antenna 3 and the fourth antenna 4.

According to the structure of the modified example 1 also, a communication device with omni-directionality and good reception characteristics is achieved, just like the structure of FIGS. 5 and 6. Thus, the loop interference of a transmission signal is reduced even when there is a reflection component of the transmission signal.

Second Example Embodiment

An antenna device 100 of a communication device according to a second example embodiment is described hereinafter with reference to FIGS. 10 and 11. FIG. 10 is an XZ plan view schematically showing the arrangement of the first antenna 1 to the fourth antenna 4. FIG. 11 is a perspective view showing the arrangement of the third antenna 3 and the fourth antenna 4. In the second example embodiment, the structures of the third antenna 3 and the fourth antenna 4 are different from those in the first example embodiment. In the antenna device 100 according to the second example embodiment, the structures of the first antenna 1 and the second antenna 2 are the same as those in the first embodiment. Thus, the illustration of the first antenna 1 and the second antenna 2 is omitted in FIG. 11.

Compared with the first example embodiment, the angle of installation of the third antenna 3 and the fourth antenna 4 is rotated horizontally by 90°. The third antenna 3 is oriented in the -X direction, and the fourth antenna 4 is oriented in the +X direction. The third antenna 3 and the fourth antenna 4 are placed at intervals from each other in the X direction. In the X direction, the first antenna 1 and the second antenna 2 are placed between the third antenna 3 and the fourth antenna 4. In the Y direction, the positions of the first antenna 1 to the fourth antenna 4 are the same.

Just like in the first example embodiment, the first antenna 1 is oriented in the -Z direction, and the second antenna 2 is oriented in the +Z direction. In the Z direction, the third antenna 3 and the fourth antenna 4 are placed between the first antenna 1 and the second antenna 2. Thus, when viewed in the XZ plane, the first antenna 1 to the fourth antenna 4 are placed on the respective sides of a square. The direction of the third antenna 3 is rotated horizontally by 90° from the direction of the second antenna 2. Thus, when the direction which the second antenna 2 is facing is rotated about the Y axis by 90°, it is the direction which the third antenna 3 is facing. Therefore, the direction of the first pair and the direction of the second pair are different by 90°.

The positional relationship of the first antenna 1 to the fourth antenna 4 has revolution symmetry. The distance from the third antenna 3 to the first antenna 1 is equal to the distance from the fourth antenna 4 to the second antenna 2. The distance from the third antenna 3 to the second antenna 2 is equal to the distance from the fourth antenna 4 to the first antenna 1. The distance from the third antenna 3 to the first antenna 1 is equal to the distance from the third antenna 3 to the second antenna 2.

Just like in the first example embodiment, when viewed in the XY plane, the feeding point 11 of the first antenna 1 and the feeding point 12 of the second antenna 2 correspond to each other. When viewed in the YZ plane, the feeding point 13 of the third antenna 3 and the feeding point 14 of the fourth antenna 4 correspond to each other. Thus, the feeding point 13 of the third antenna 3 and the feeding point 14 of the fourth antenna 4 are placed at positions that are mirror images of each other.

15

The first antenna **1** and the second antenna **2** are used for V polarization, and the third antenna **3** and the fourth antenna **4** are used for H polarization. A transmission signal of the first antenna **1** and a transmission signal of the second antenna **2** are in phase by the positional relationship between the feeding point **11** and the feeding point **12**. By combining a received signal of the third antenna **3** and a received signal of the fourth antenna **4** in opposite phase, the interference components are cancelled. Further, a transmission signal of the third antenna **3** and a transmission signal of the fourth antenna **4** are in phase by the positional relationship between the feeding point **13** and the feeding point **14**. Thus, by combining a received signal of the first antenna **1** and a received signal of the second antenna **2** in phase, the interference components are cancelled. In the structure of this example embodiment, the same effects as in the first example embodiment are obtained. Note that a receiving circuit is the same as that of the first example embodiment, and the description thereof is omitted.

Other Example Embodiment

A communication device **300** according to another example embodiment is described hereinafter with reference to FIG. 12. Note that description that is redundant with the above description of the first example embodiment is omitted as appropriate. The communication device **300** includes a first antenna **1**, a second antenna **2**, a third antenna **3**, a fourth antenna **4**, and a receiving circuit **220**.

The first antenna **1** is a first directional antenna that is oriented in a first direction and transmits and receives a signal with a first polarization. The second antenna **2** is a second directional antenna that is oriented in a second direction, which is opposite to the first direction, and transmits and receives a signal with the first polarization. The second antenna **2** forms a first pair **31** with the first antenna **1**. The third antenna **3** is a third directional antenna that is oriented in a third direction, which is a direction obtained by horizontally rotating the second direction by 90° or 180°, and transmits and receives a signal with a second polarization orthogonal to the first polarization. The fourth antenna **4** is a fourth directional antenna that is oriented in a fourth direction, which is opposite to the third direction, and transmits and receives a signal with the second polarization orthogonal to the first polarization. The fourth antenna **4** forms a second pair **32** with the third antenna **3**. The first antenna **1** is provided with a feeding point **11** (first feeding point). The second antenna **2** is provided with a feeding point **12** (second feeding point) that is placed in phase with the feeding point **11**. The third antenna **3** is provided with a feeding point **13** (third feeding point). The fourth antenna **4** is provided with a feeding point **14** (fourth feeding point) that is placed in opposite phase to the feeding point **13**. The receiving circuit **220** adjusts at least one of the amplitude and phase of a received signal received by the first pair **31** or the second pair **32** and demodulates the received signal. As an example of two types of polarization, the first polarization may be a vertical polarization, and the second polarization may be a horizontal polarization.

Although the present disclosure is described above with reference to the example embodiments, the present disclosure is not limited to the above-described example embodiments. Various changes and modifications as would be obvious to one skilled in the art may be made to the structure and the details of the present disclosure without departing from the scope of the disclosure.

16

According to the present disclosure, there are provided a communication device and a communication method with omni-directionality and good reception characteristics.

The first and second example embodiments can be combined as desirable by one of ordinary skill in the art.

While the disclosure has been particularly shown and described with reference to example embodiments thereof, the disclosure is not limited to these embodiments. It will be understood by those of ordinary skill in the art that various changes in form and details may be made therein without departing from the spirit and scope of the present disclosure as defined by the claims.

What is claimed is:

1. A communication device comprising:
a first directional antenna oriented in a first direction and configured to transmit and receive a signal with a first polarization;
a second directional antenna oriented in a second direction opposite to the first direction and configured to transmit and receive a signal with the first polarization and form a first pair with the first directional antenna;
a third directional antenna oriented in a third direction obtained by horizontally rotating the second direction by 90° or 180° and configured to transmit and receive a signal with a second polarization orthogonal to the first polarization;
a fourth directional antenna oriented in a fourth direction opposite to the third direction and configured to transmit and receive a signal with the second polarization and form a second pair with the third directional antenna;
a first feeding point provided in the first directional antenna;
a second feeding point provided in the second directional antenna and placed in phase with the first feeding point;
a third feeding point provided in the third directional antenna;
a fourth feeding point provided in the fourth directional antenna and placed in opposite phase to the third feeding point; and
a receiving circuit configured to adjust at least one of an amplitude and a phase of a received signal received by the first pair or the second pair and demodulate the received signal.
2. The communication device according to claim 1, wherein the receiving circuit adjusts at least one of an amplitude and a phase of the received signal based on signal quality of the demodulated received signal.
3. The communication device according to claim 2, wherein the receiving circuit comprises:
an analog to digital converter configured to convert two received signals received by the first pair or the second pair from analog-to-digital;
a weight multiplier configured to multiply the analog to digital converted received signals by a combined complex weight;
an adder configured to add the received signals multiplied by the combined complex weight;
a demodulation circuit configured to perform demodulation of the integrated received signal; and
a control circuit configured to control the combined complex weight based on signal quality of the demodulated received signal.
4. The communication device according to claim 2, wherein the receiving circuit comprises:
a phase shifter configured to adjust phases of two received signals received by the first pair or the second pair;

17

a variable distributor configured to combine the received signals with adjusted phases;
 a demodulation circuit configured to demodulate the received signal combined by the variable distributor; and
 a control circuit configured to control the phase shifter and the variable distributor based on signal quality of the demodulated received signal.

5. The communication device according to claim 1, wherein the first to fourth directional antennas are patch antennas.

6. The communication device according to claim 1, wherein

the first feeding point and the second feeding point are placed so as to overlap each other when viewed in a plan view from an antenna surface side of the first directional antenna, and

the third feeding point and the fourth feeding point are placed so as to overlap each other when viewed in a plan view from an antenna surface side of the third directional antenna.

7. The communication device according to claim 1, wherein

the first directional antenna and the second directional antenna are placed opposite to each other and facing in opposite directions, and

the third directional antenna and the fourth directional antenna are placed opposite to each other and facing in opposite directions.

8. A communication method comprising:

a step of performing one of transmission and reception by using a first pair including a first directional antenna provided with a first feeding point and a second directional antenna provided with a second feeding point;

a step of performing another one of transmission and reception by using a second pair including a third directional antenna provided with a third feeding point and a fourth directional antenna provided with a fourth feeding point; and

a step of adjusting at least one of an amplitude and a phase of a received signal received by the first pair or the second pair and demodulating the received signal, wherein

the first directional antenna and the second directional antenna transmit and receive a signal with a first polarization,

the third directional antenna and the fourth directional antenna transmit and receive a signal with a second polarization orthogonal to the first polarization,

the first directional antenna is oriented in a first direction, the second directional antenna is oriented in a second direction opposite to the first direction,

the third directional antenna is oriented in a third direction obtained by horizontally rotating the second direction by 90° or 180°,

18

the fourth directional antenna is oriented in a fourth direction opposite to the third direction, the first feeding point and the second feeding point are placed in phase with each other, and the third feeding point and the fourth feeding point are placed in opposite phase to each other.

9. The communication method according to claim 8, wherein at least one of an amplitude and a phase of the received signal is adjusted based on signal quality of the demodulated received signal.

10. The communication method according to claim 8, comprising:

converting two received signals received by the first pair or the second pair from analog to digital; multiplying the analog to digital converted received signals by a combined complex weight; integrating the received signals multiplied by the combined complex weight; performing demodulation of the integrated received signal; and controlling the combined complex weight based on signal quality of the demodulated received signal.

11. The communication method according to claim 8, comprising:

adjusting phases of two received signals received by the first pair or the second pair; combining the received signals with adjusted phases; demodulating the combined received signal; and controlling an amplitude or a phase of the received signal based on signal quality of the demodulated received signal.

12. The communication method according to claim 8, wherein the first to fourth directional antennas are patch antennas.

13. The communication method according to claim 8, wherein

the first feeding point and the second feeding point are placed so as to overlap each other when viewed in a plan view from an antenna surface side of the first directional antenna, and

the third feeding point and the fourth feeding point are placed so as to overlap each other when viewed in a plan view from an antenna surface side of the third directional antenna.

14. The communication method according to claim 8, wherein

the first directional antenna and the second directional antenna are placed opposite to each other and facing in opposite directions, and

the third directional antenna and the fourth directional antenna are placed opposite to each other and facing in opposite directions.
